ERNEST S. BULLARD AND VICTOR H. LEINER, OF WHEELING, WEST VIRGINIA.

INTERNAL-COMBUSTION ENGINE.

1,189,660.

Specification of Letters Patent.

Patented July 4, 1916.

Application filed September 27, 1915. Serial No. 52,809.

To all whom it may concern:

Be it known that we, ERNEST S. BULLARD and VICTOR H. LEINER, citizens of the United States of America, and residents of Wheeling, county of Ohio, and State of West Virginia, have invented certain new and useful Improvements in Internal-Combustion Engines, of which the following is a specification.

10 This invention relates broadly to internal combustion engines, and it has for its primary object to provide an engine in which piston valves are employed for controlling the inlet and the exhaust of the gases, securing greater efficiency with a minimum expenditure of waste energy.

A further object is to provide, in a gas engine, an exhaust valve of the piston type which is so located that it is directly acted 20 upon by the exploding gas, and the impulse given thereto is communicated to the crank-shaft, materially assisting at the commencement of the power stroke in carrying over center the crank with which the associated power piston is connected.

A still further object is to provide an engine having an inlet valve of piston type which is so arranged that it compresses air in a pocket during the suction and compression strokes of the power piston and is then acted upon by the re-expanding air during the power stroke for further assisting in carrying said crank over center.

Another object is to provide a structure 35 in which the power cylinder and a piston valve chamber are in open communication and in which a piston valve operating in said chamber co-operates with the power piston for compressing the charge.

40 Another object within the contemplation of the invention is to provide a valve construction and arrangement for gas engines which shall possess numerous and varied advantages over the usual or common forms 45 of spring-held puppet valves.

With these and other important objects in view, the invention resides in the features of construction, arrangement of parts and combinations of elements which will herein- 50 after be fully described, reference being had to the accompanying drawings, forming a part of this specification, in which—

Figure 1 is a vertical sectional view of the invention showing the parts occupying 55 the positions assumed at the commencement of the inlet or suction stroke; Figs. 2, 3 and

4 are similar sections, reduced, respectively illustrating the positions assumed by the parts at the beginning of the compression, power and exhaust strokes. Fig. 2 further 60 illustrates a slight modification; Fig. 5 is a partial section similar to Fig. 1, illustrating a second modification; and Fig. 6 is a horizontal section on line 6—6, Fig. 3.

Referring to said drawings, in which like 65 designating characters distinguish like parts throughout the several views—1 indicates an engine cylinder in which reciprocates the usual power piston 2 connected to the crank-shaft 3 by the connecting rod 4 in the ordinary manner. Mounted on the crank-shaft at a suitable point is a gear 5 which meshes with suitably proportioned gears 6 and 7 fixed, respectively, on shafts 8 and 9 disposed parallel to said crank shaft and connected by connecting rods 10 and 11 to piston valves 12 and 13 operating in cylindrical valve chambers 14 and 15 and controlling, respectively, the inlet and exhaust of gases. Said valve chambers are located at opposite sides of the cylinder. The admission of gas to the inlet valve chamber 14 is through a suitably located port 16, and said gas is thence preferably admitted to the explosion chamber 17 at the upper end of the power cylinder 1 through an upwardly inclined port or passage 18, as shown in Figs. 1, 3 and 4. The exhaust valve chamber 15 is permanently in open communication at its upper end with the explosion chamber 17 80 85 90 95

for a purpose which will presently be explained, and the exhaust gases pass from said chamber through an appropriately located port 19 leading outward from said chamber 15.

As in the case of practically all gas engines, the explosion of the gas occurs more or less in advance of the instant at which the crank to which connecting-rod 4 is attached reaches a vertical, or central, position—a 100 fact which renders necessary the employment of the usual fly-wheel. In the present invention, due to the fact that the top of the exhaust valve chamber 15 and the explosion chamber 17 are in direct open communication, the explosion acts directly upon the exhaust piston valve 13, which is at the moment beginning its downward movement, forcing the latter downward and, consequently, assisting in large measure, 110 through the intermediate connecting rod 11 and gears 9 and 5, to carry the latter over

said central position. For facilitating this action a spark-plug opening 20 is preferably provided at a point directly over the valve chamber 15 so that the initial part 5 of the explosion will occur directly over the exhaust valve 13, giving the latter an initial impulse slightly in advance of the instant when the power piston 2 receives the full force of the explosion. The gearing of the 10 shafts 8 and 9 is such that the power piston makes two strokes to each stroke of the inlet and exhaust valves, and also that said valves alternate one with the other in their movements, the inlet valve being accurately 15 timed to begin to open inlet port 16 with the beginning of the suction stroke of the power piston and to close said port slightly following the beginning of the compression stroke of said piston, as shown in Figs. 1 20 and 2, respectively; and the exhaust valve being also timed to begin to open exhaust port 19 near the end of the power stroke of the piston and to close said port at the end of the exhaust stroke, as is best shown 25 in Figs. 4 and 1, respectively.

The lower end of the inclined passage 18 is disposed in the same horizontal plane with inlet port 16 and is consequently opened and closed simultaneously with the opening and closing of the latter, as is obvious. 30 That portion of the inlet valve chamber 14 which lies above the plane of the port 16 constitutes a pocket in which gas or air is compressed during that portion of the 35 upward movement of the inlet valve 12 which occurs during the compression and explosion strokes of the power piston. The return movement of said valve which occurs during the exhaust stroke of the piston 40 ton is facilitated by the expansion of the air or gas so compressed in said pocket. Thus it will be seen that the only momentous waste of power in the operation of the engine, which resides in that expended as 45 aforesaid in compressing the air in the pocket, is particularly recovered in returning the valve 12 and such recovery is had at a time when it is utilized in assisting the crank to which the power piston is connected to pass over dead center, or the lowermost position assumed by said crank. 50

In the modification illustrated in Fig. 2, the opposite sides of the device are made symmetrical, the upper end of the inlet 55 valve chamber 14 being in open communication with the explosion chamber 17 precisely as is the exhaust valve chamber 15. While this construction may be employed, it is open to the objection that the inlet 60 valve is subjected to a portion of the force of the explosion at a time when said valve is moving upward, as shown in Fig. 3.

In the modification illustrated in Fig. 5, the inlet piston valve 12 and the chamber 65 14 are omitted, in which case any ordinary

form of puppet valve may be substituted, as, for example, a spring-held valve 21 of puppet type, said valve being located in the cylinder head 24 at an appropriate point, as directly over the explosion chamber 17. 70

From the foregoing it will be seen that the invention is free from many of the objectionable features found in those types of engines in which sleeve valves and puppet valves are used, chief among such objectionable features being that such valves require the expenditure of considerable force to effect their opening, become stuck and do not readily permit proper scavenging; such valves are a source of much noise 80 and clatter, requiring frequent adjustment; such valves and their seats collect carbon, become worn and consequently require frequent grinding; and the springs by which such valves are held seated become weak 85 and break. The valves of the present invention are noiseless and positively driven, and permit free and unobstructed admission of live gases and exhaust of spent gases with a minimum of energy wasted. Further, it 90 will be noted that ample splash lubrication for the piston valve is afforded by the structure shown.

As is obvious, a second spark plug opening 23 may be provided in the head 24 of the cylinder, as shown in Fig. 1, so that two plugs may be employed when desired.

What is claimed is—

1. In an internal combustion engine, a power cylinder, a piston reciprocating therein, inlet and exhaust valve chambers located laterally of said cylinder, inlet and exhaust ports respectively provided in the walls of said chambers, reciprocating piston valves in said chambers, the exhaust chamber being in permanent open communication with the cylinder above the limit of upward movement of its valve, and the inlet chamber being in communication with said cylinder through a side-opening passage which is closed by its valve during the power stroke of the piston so that the side wall of said valve receives the impact of the explosion, said passage being so located with respect to the inlet port that unobstructed communication is had therebetween over the extreme upper end of said valve throughout the suction stroke of the piston. 110

2. In an internal combustion engine, a power cylinder, a piston for reciprocating therein, inlet and exhaust valve chambers located laterally of said cylinder, the exhaust chamber being in permanent open communication with said cylinder above the limit of upward movement of said piston, reciprocating piston valves in said valve chambers, said chambers having ports in the outer walls thereof, the inlet valve chamber being in communication with said cylinder through a passage leading from a point therein hori- 125 130

zontally alined with the port thereof, and means for synchronously moving said valves to cover and uncover said ports, said passage being opened and closed respectively by the 5 piston valve of the inlet chamber simultaneously with the opening and closing of the inlet ports.

3. In an internal combustion engine, a power cylinder, a piston for reciprocating therein, inlet and exhaust valve chambers located laterally of said cylinder, the exhaust chamber having its upper end in permanent open communication with said cylinder above the limit of upward movement of said piston, unapertured reciprocating piston valves in said valve chambers, said chambers having ports in the outer walls thereof, the inlet valve chamber being in communication with the upper end of 20 said cylinder through an inclined passage leading from a point therein horizontally alined with the port thereof, so that it is opened and closed by the piston simultaneously with the opening and the closing of 25 the inlet port, a pocket being formed in said inlet valve chamber above said alined passages wherein gas is compressed by upward movement of said piston valve for forcibly returning said valve to assist the power 30 piston crank to pass over dead center.

4. In an internal combustion engine, the combination with a power cylinder having an explosion chamber at the upper end thereof, of a piston for reciprocating in said cylinder, inlet and exhaust valve chambers located laterally with respect to said cylinder and having ports in the outer walls thereof below the level of said explosion chamber, a piston valve reciprocating in 40 each of said chambers, means for synchronously moving said valves for covering and uncovering said ports, the exhaust chamber having its upper end in open communication with said cylinder above the limit of upward movement of the piston to permit the 45 valve to receive a downward impulse under the force of the explosion, and an inclined

passage for live gas leading into the upper end of said cylinder from a point in the inlet chamber horizontally alined with the inlet port, said passage and said inlet port being simultaneously opened and closed by the 50 piston valve of the inlet chamber.

5. In an internal combustion engine, a power cylinder, a piston for reciprocating therein, inlet and exhaust valve chambers located laterally of said cylinder, the exhaust chamber being in permanent open communication with said cylinder above the limit of upward movement of said piston and the inlet chamber being closed at its upper end against such communication, reciprocating piston valves in said valve chambers, said chambers having ports therein controlled by 55 said valves, and the inlet chamber being in communication with the upper end of said cylinder through an inclined passage leading from a point therein located close above the top of the inlet valve when the latter occupies the limit of its downward movement, so that live gas entering the inlet chamber passes unobstructedly over the top of said valve in reaching said passage.

6. In an internal combustion engine, a power cylinder, a piston reciprocating therein, inlet and exhaust valve chambers located laterally of said cylinder, said chambers having ports located in the walls thereof, reciprocating piston valves in said chambers, the exhaust chamber being in permanent open communication with the cylinder above the limit of upward movement of said piston, and the inlet chamber being in communication with said cylinder through a passage which is uncovered by its piston 80 valve during the suction stroke of the piston.

In testimony whereof we affix our signatures in presence of two witnesses.
